UNITED STATES PATENT OFFICE.

JOSHUA LEGG, OF RUSHVILLE, NEW YORK.

IMPROVEMENT IN HORSESHOERS' RESTS.

Specification forming part of Letters Patent No. 141,651, dated August 12, 1873; application filed August 19, 1871.

To all whom it may concern:

Be it known that I, JOSHUA LEGG, of Rushville, in the county of Yates and State of New York, have invented certain Improvements in Horseshoer's Rest, of which the following is a specification:

My invention relates to the construction and application of a rest for horseshoers to place the foot of the horse upon while clinching the nails and rasping the hoof, and making the top of the rest so small that the sole of the horse's foot may rest upon it and allow the shoer to use the ordinary clinching-iron all around the shoe without moving the horse's foot.

The figure is an elevation, showing the rest in the position it is used.

A is one of the three legs that constitutes the main portion of the rest upon which it stands. They may be made of wood or iron, and of any size or length required by various shoers. When made of wood it should be bent, so that the lower ends may be placed far enough apart to make it stand firm, and have the upper ends firmly united together, and be held by a band or bolts. When made of iron the upper ends may be welded together, if preferred. B is a band that surrounds and holds the upper end of the legs together. It must be made so small that the shoer may pass his clinching-iron to each nail in the horseshoe without moving the horse's foot to complete the operation of clinching.

I am aware of the patent to J. C Tucker, dated February 5, 1867, and do not claim anything therein shown or described; but

I claim—

A horseshoer's rest, made with three legs united at their upper ends, forming a rest on their top smaller than the inner circle of the horseshoe, substantially as specified.
